UNITED STATES PATENT OFFICE.

FREDERICK A. FELDKAMP, OF NEWARK, NEW JERSEY.

FUSE-CARTRIDGE.

1,268,807.

Specification of Letters Patent. Patented June 4, 1918.

Application filed March 31, 1917, Serial No. 158,809. Renewed April 29, 1918. Serial No. 231,570.

To all whom it may concern:

Be it known that I, FREDERICK A. FELDKAMP, a citizen of the United States, residing at Newark, in the county of Essex and State of New Jersey, have invented certain new and useful Improvements in Fuse-Cartridges; and I do hereby declare the following to be a full, clear, and exact description of the invention, such as will enable others skilled in the art to which it appertains to make and use the same, reference being had to the accompanying drawings, and to characters of reference, marked thereon, which form a part of this specification.

15 The present invention relates, generally, to improvements in fuse cartridges; and the invention has reference, more particularly, to an improved construction of multiple fuse cartridge.

20 The present invention has for its principal object to provide improvements in and simplification of the construction of multiple fuse cartridges of the general type shown and described in a previous application for Letters-Patent filed by me on November 6th, 25 1916, Serial Number 129,645/15, now patent No. 1,254,490, Jan. 22, 1918.

Another object of the present invention is to provide a means whereby when one of the several fuse elements is connected in circuit with the end or terminal caps, the contact receiving devices of the remaining fuse elements are properly and completely insulated against short-circuiting with each other, or against the current jumping to the movable terminal cap or contact closing devices.

Other objects of this invention, not at this time more particularly enumerated, will be clearly understood from the following detailed description of the same.

With the various objects of this invention in view, the same consists, primarily, in the novel construction of multiple fuse cartridge hereinafter set forth; and, furthermore, the invention consists in the novel arrangements and combinations of the various parts, as well as in the details of the construction thereof, all of which will be hereininafter more fully described and claimed.

The invention is clearly illustrated in the accompanying drawings, in which:

Figure 1 is a side elevation of the improved construction of multiple fuse cartridge; Fig. 2 is a longitudinal section of the same, the interior parts thereof being

shown in elevation; and Fig. 3 is a longitudinal vertical section taken on line 3-3 in said Fig. 2.

Fig. 4 is a cross section taken on line 4-4 in said Fig. 2; Fig. 5 is a cross section taken on line 5-5 in said Fig. 2; Fig. 6 is a cross section taken on line 6-6 in said Fig. 2; all of said sections being viewed in the direction of the arrow *x*.

Fig. 7 is a cross section taken on line 7-7 in said Fig. 2, looking in the direction of the arrow *x*; and Fig. 8 is a cross section taken on line 7-8 in said Fig. 2, looking in the direction of the arrow *y*.

Fig. 9 is a transverse longitudinal section taken on line 9-9 in said Fig. 5, looking in the direction of the arrow *z*.

Fig. 10 is a fragmentary longitudinal cross section of a slightly modified construction of my novel multiple fuse cartridge; and Fig. 11 is a cross section thereof taken on line 11-11 in said Fig. 10 looking in the direction of the arrow *a*.

Fig. 12 is a longitudinal cross section of another modified construction of my novel multiple fuse cartridge; and Fig. 13 is a cross section thereof taken on line 13-13 in said Fig. 12.

Similar characters of reference are employed in all of the hereinabove described views, to indicate corresponding parts.

Referring now to said drawings, the reference character 1 indicates a tubular casing constructed of some suitable insulating material: One end of said tubular casing is closed by a fixed metallic terminal cap 2, which telescopes over the exterior surface of said casing 1, and which is immovably fixed in such relation, as by means of an inwardly turned marginal bead or flange 3 which is engaged in an annular groove 4 provided in said exterior surface of said casing 1. The opposite end of said casing 1 is closed by a movable terminal cap 5, which telescopes over the exterior surface of said casing 1, and which is so connected therewith as to be capable of both a longitudinal movement and a rotary movement relative thereto. The means for so securing the movable terminal cap 5 comprises an inwardly turned annular shoulder or rim 6, formed at the inner marginal edge of said terminal cap 5, which is engaged in an annular cutaway portion 7, formed in the exterior surface of said casing 1. The provision of this cutaway portion 7 serves also

to form an exterior annular shoulder or stop-portion 8 at the end of said casing, against which said shoulder or rim 6 of said cap 5 is stopped to arrest outward longitudinal movement thereof.

The reference character 9 indicates a plug or contact pin carrier which is made of some suitable insulating or non-conducting material. This plug or contact pin carrier is disposed within the casing 1 by inserting the same within that end of the latter upon which is arranged said movable metallic terminal cap 5. The outer end 10 of said plug or carrier 9 is permitted to project slightly beyond the end of said casing 1, thus providing an annular space 11 between said end 10 and the sides of said movable terminal cap 5; the purpose of said space 11 will be subsequently defined. Said plug or carrier 20 is immovably fixed, in the relation to said casing 1, as above described, by means of transverse fastening pins 12, which are driven through the sides of said casing 1, and thence into the body of said plug or carrier.

Preferably, the interior sides of said casing 1 are provided with longitudinally directed channels or grooves 13, spaced equidistant one from another. The inner end of said plug or carrier 9 is provided with transverse grooves 14, preferably providing an X-shape, the outer ends of which register or align themselves with said channels or grooves 13.

The reference character 15 indicates a partition member, which is preferably X-shape in cross section, the same being made of some suitable insulating or non-conducting material. The outer marginal edges of said partition member, thus formed, are received in said channels or grooves 13, and the inner end of the same projects or dovetails into said X-shaped grooves 14 in the said plug or carrier 9, thereby holding said partition member immovably related to the casing 1, and arranged to divide the interior of the latter into a plurality of separate longitudinally extending fuse chambers or compartments 16, the inner ends of which are closed by said plug or carrier 9, against which the inner end of said partition member abuts. The opposite or outer end of the partition member 15 terminates, preferably, some distance short of the end wall of said fixed terminal cap 2, and said end is cut away at the converging point of its branches to provide a receiving seat 17, the purpose of which will presently appear.

The reference character 18 indicates a plurality of contact-pins. Said contact-pins 18 are passed longitudinally through said plug or carrier 9, and embedded therein, being thus insulated one from another. As thus disposed said contact-pins parallel each other through the respective quarters of said

70 plug or carrier, and so that their inner ends 19 project respectively into the respective fuse-chambers or compartments 16. The outer end of said plug or carrier 9 is provided with a plurality of countersunk chambers or openings 20 into which the outer ends or male contact members 21 of said respective contact-pins 18 project so as to be centrally and longitudinally disposed within said respective chambers or openings 20. 75 Said outer ends or male contact members 21 of said contact-pins 18 are provided with cross cuts or splits 22 for purposes herein-after explained.

Seated within the receiving-seat 17, at the 80 outer end of said partition member 15, is the spreader-head 23 of a contact-post 24, the end of which is riveted, or otherwise secured, both mechanically and electrically, to the end wall of said fixed terminal cap 2.

The reference-character 25 indicates a plurality of fuse-elements or wires. One end of each fuse-element or wire is secured to an inner end 19 of said contact-pins 18, preferably by inserting and soldering the 90 same within a longitudinally and inwardly extending bore formed in each inner end 19 of said respective contact-pins 18, and then the fuse-element or wire is carried longitudinally through a fuse-chamber or compartment 16, passed over said spreader-head 23, and then secured to said contact-post 24 by forming an embracing convolution 26 about the latter, or said fuse-element or wires may be secured to said contact-post 24 100 in any other suitable manner deemed desirable. When the convolutions 26 are employed, however, the fixity of the connection of said fuse-elements or wires may be assured by washing said convolutions with 105 solder. In this manner, it will be apparent, that each fuse-element or wire is separately and individually inclosed within its own fuse-chamber or compartment, and that each fuse-element or wire has a permanent electrical connection with said fixed terminal cap 2.

The means for connecting said plurality of fuse-elements or wires, individually, successively or selectively in an electric circuit 115 to be served thereby, comprises a tubular female contact member 27 having a longitudinal receiving opening 28, and which is secured, both mechanically and electrically to the outer wall of said movable terminal 120 cap 5, and in position to extend or project longitudinally toward said plug or carrier 9 and the contact-pins 18 carried thereby.

Secured against the inner side of said end wall of said movable terminal cap 5 is an 125 insulating cover or shield-piece 29, the same being cutaway, as at 30, so that it may straddle the body of said inwardly projecting female contact member 27. Said insulating cover or shield-piece 29, is secured in 130

place and in operative fixed association with said movable terminal cap 5 by means of inwardly pressed tongues, lugs or holding ears 31, which are forced out of the body of the 5 side walls of said movable terminal cap so as to engage the marginal edges of said cover or shield-piece 29, and thus hold the same in normal operative position against the inner side of the end wall of said movable terminal cap 5. Said female contact member 27 is selectively caused to electrically engage and contact with the bifurcated male contact member 21 of one of said contact-pins 18 by entering a chamber or opening 20 in 10 which the male contact-member 21 is situated so as to telescope over the same and receive it within the receiving opening 28 thereof, when said movable terminal cap 5 is moved inwardly to its normal operative 15 relation to said casing 1; the cross cuts or splits 22 of said male contact member 21 rendering the bifurcated portions thereof slightly yieldable so as to assure, by the compression of said parts within the opening 28, 20 a good electrical contact therewith. When the movable terminal cap 5 is thus moved inwardly and thereupon electrically connected with one of the fuse elements 25, said insulating cover or shield-piece 29 extends over 25 and closes all the remaining chambers or openings 20 in which the other male contact members 21 are situated, thus entirely segregating the latter, and thus assuring their complete electrical insulation against any 30 likelihood of short circuiting with other parts and against any likelihood of the current jumping to the terminal cap 5 from said male contact members 21 not desired in circuit. When said movable terminal cap 5 is 35 thus moved inwardly to operative position, the said tongues, lugs or holding ears 31, which retain said cover or shield-piece 29 are received in the annular space 11 between the projecting end 10 of said plug or carrier 40 9 and the walls of said terminal cap 5.

The said casing 1 may be provided on its exterior surface, adjacent to said movable terminal cap 5, with suitable graduations or indicating marks 32 denoting the position of 45 said respective fuse-elements 25 and their male contact members 21, and in like manner, the exterior surface of said movable terminal cap 5 may be provided with a suitable indicating mark 33 denoting the position 50 of said female contact-member 27, so that by selectively registering the mark 33 with one of the marks 32, the female contact-member 27 may be brought into electrical contact with a desired male contact member 21, by drawing out, turning and pushing back said movable terminal cap 5, and the fuse element 25 connected with the latter is thus electrically connected with said movable terminal cap 5.

60 When one of the fuse-elements or wires 25

is thus electrically connected between the respective terminal caps 2 and 5, the cartridge may be connected in the electric circuit to be served by inserting the respective terminal caps 2 and 5 between the usual 70 spring-like receiving clips connected in said circuit in the well known manner, so that the current passes from the fixed terminal cap 2 through the fuse-element or wire and thence back to the line through said movable terminal cap 5, or vice versa. 75

It will be understood that each fuse chamber or compartment 16, as well as the space surrounding the contact-post 24, is adapted to be filled with the usual filler powder, or 80 similar material, such as is commonly used in fuse cartridges to absorb the vapors generated by the burning of the fuse element or wire, although in order not to interfere with the clear illustration of the mechanical 85 construction of my invention, graphic illustration of such powder has been omitted from the drawings.

Referring now to Figs. 10 and 11 of the drawings, I have illustrated a slightly modified construction of my invention, the chief modification lying in the structure of the plug or carrier 9 and its relation to the casing 1 and movable terminal cap 5. In this construction the main portion of the plug 95 or carrier 9 is enlarged in diameter to equal the diameter of the casing 1, and the inner end 34 thereof is of reduced diameter so as to telescope into the end of the casing 1 and then secured by the pins 35. The annular 100 cut-away portion 7 and stop portion 8 is formed in the outer surface of the plug or carrier 9, and the rim 6 of the cap 5 associated therewith, in all other respects this structure is similar to that already above 105 described, and the operation thereof is substantially the same.

Referring now to Figs. 12 and 13 of the drawings, I have illustrated still another modified construction of my invention, comprising a main body or casing 36 to one end of which a fixed terminal cap 37 is secured. Formed in said main body are a plurality of longitudinally extending tubular chambers or compartments 38. Contact posts 39, 115 which are secured to said fixed terminal cap, enter each chamber or compartment 38, and to each of said contact posts a fuse element or wire 40 is secured so as to respectively extend through said chambers or compartments 38; the inner ends of said compartments or chambers 38 are closed by an integrally formed contact carrying portion 41 of said main body or casing 36, through which contact-pins 42 extend into each 120 chamber or compartment 38, said fuse elements or wires being secured respectively to said contact-pins 42. The outer end of the casing or main body 36 is provided with the chambers or openings 43 in which the 125 130

male contact members 44 of said contact pins 42 are situated. A movable terminal cap 45 is arranged upon this end of the main portion or casing 36, an annular cutaway portion 46 and stop 47 being provided in the latter with which the marginal rim or flange 48 of said terminal cap 45 is operatively associated. Said movable terminal cap is provided with the female contact member 49 adapted to selectively engage the male contact members 44, and the insulating cover or shield-piece 50 is secured upon the inner side of the end wall of said movable terminal cap for the purposes described. The operation of this construction of my invention is substantially the same as already above described.

By "fixed terminal cap" in the claims, I refer to the cap that is at the opposite end from the terminal caps 5 and 45; but do not intend to limit myself necessarily to a cap or other terminal that has no movement with respect to the casing.

I claim:—

25 1. A multiple fuse cartridge comprising a casing subdivided longitudinally into a plurality of individual fuse compartments, external terminal caps on the opposite ends of said casing one of which is capable of movement relative to said casing, a fuse element in each fuse compartment electrically connected with one external terminal cap, contact-pins to which the opposite ends of said fuse elements are respectively connected, 30 means for mounting said contact-pins in insulated relation one to another, a male contact member formed at the outer end of each contact-pin, and a female contact member electrically connected with the movable 35 terminal cap for selective engagement with said male contact members.

2. A multiple fuse cartridge comprising a casing subdivided longitudinally into a plurality of individual fuse compartments, external terminal caps on the opposite ends of said casing one of which is capable of movement relative to said casing, a fuse element in each fuse compartment electrically connected with one external terminal cap, 40 contact-pins to which the opposite ends of said fuse elements are respectively connected, means for mounting said contact-pins in insulated relation one to another, a male contact member formed at the outer end of each contact-pin, a female contact member 45 electrically connected with the movable terminal cap for selective engagement with said male contact members, and a shield of insulating material secured within said movable terminal cap adapted to cover and insulate the remaining male contact members when said female contact member is engaged with one male contact member.

3. A multiple fuse cartridge comprising a casing subdivided longitudinally into a

plurality of individual fuse compartments, an external fixed terminal cap mounted on one end of said casing, an external movable terminal cap mounted on the opposite end of said casing, a carrier portion of insulating material secured within said opposite end of said casing, a plurality of contact-pins extending longitudinally through said carrier portion and respectively into each fuse-compartment, a fuse element in each fuse compartment, one end of each fuse element being electrically connected with said fixed terminal cap, the opposite end of each fuse element being respectively electrically connected with a contact-pin, a male contact member connected with the outer end of each contact-pin, said carrier portion having counter-sunk openings or chambers in its outer end within which said male contact members are respectively situated, and a female contact member having a receiving opening carried by said movable terminal cap adapted upon manipulation of the latter to be selectively moved into a counter-sunk opening or chamber in said carrier portion and there engaged with a male contact member.

4. A multiple fuse cartridge comprising a casing subdivided longitudinally into a plurality of individual fuse compartments, an external fixed terminal cap mounted on one end of said casing, an external movable terminal cap mounted on the opposite end of said casing, a carrier portion of insulating material secured within said opposite end of said casing, a plurality of contact-pins extending longitudinally through said carrier portion and respectively into each fuse-compartment, a fuse element in each fuse compartment, one end of each fuse element being electrically connected with said fixed terminal cap, the opposite end of each fuse element being respectively electrically connected with a contact-pin, a male contact member connected with the outer end of each contact-pin, said carrier portion having counter-sunk openings or chambers in its outer end within which said male contact members are respectively situated, a female contact member having a receiving opening carried by said movable terminal cap adapted upon manipulation of the latter to be selectively moved into a counter-sunk opening or chamber in said carrier portion and there engaged with a male contact member, and a shield of insulating material secured against the inner side of said end wall of said movable terminal cap adapted to cover the openings or chambers and thus insulate the remaining male contact members when said female contact member is engaged with one male contact member.

5. In a multiple fuse cartridge, a casing having external terminal caps on its opposite ends one of which is a fixed cap and the

- other capable of movement relative to said casing, a plurality of fuse-elements within said casing electrically connected at one end with the fixed terminal cap, insulated contact pins having split male contact members at their outer ends to which the opposite ends of said fuse-elements are respectively electrically connected, a female contact member carried by said movable terminal cap adapted upon manipulation of the latter to be selectively engaged with a male contact member.
6. In a multiple fuse cartridge, a casing having external terminal caps on its opposite ends one of which is a fixed cap and the other capable of movement relative to said casing, a plurality of fuse-elements within said casing electrically connected at one end with the fixed terminal cap, insulated contact pins having split male contact members at their outer ends to which the opposite ends of said fuse-elements are respectively electrically connected, a female contact member carried by said movable terminal cap adapted upon manipulation of the latter to be selectively engaged with a male contact member, and a shield of insulating material secured within said movable terminal cap so as to cover and insulate the remaining male contact members when said female contact member is engaged with one male contact member.
7. In a fusible circuit breaker the combination with the fuse elements thereof of contact-pins, a carrier plug of insulating material in which said contact-pins are embedded, the outer ends of said contact-pins having split or bifurcated portions forming male contact members, said carrier plug having inwardly extending chambers in which said male contact members are respectively inclosed, a movable terminal cap, and a female contact member connected with said movable terminal cap adapted upon manipulation of the latter to be selectively entered within a chamber and engaged with said male contact member located therein.
8. In a fusible circuit breaker the combination with the fuse elements thereof of contact-pins, a carrier plug of insulating material in which said contact pins are embedded, the outer ends of said contact-pins having split or bifurcated portions forming male contact members, said carrier plug having inwardly extending chambers in which said male contact members are respectively inclosed, a movable terminal cap, a female contact member connected with said movable terminal cap adapted upon manipulation of the latter to be selectively entered within a chamber and engaged with said male contact member located therein, and a shield of insulating material secured within said movable cap adapted to register over and close the remaining chambers and thus insulate the remaining male contact members when said female contact member is engaged with one male contact member.

In testimony, that I claim the invention set forth above I have hereunto set my hand this 29th day of March, 1917.

FREDERICK A. FELDKAMP.
